UNITED STATES PATENT OFFICE.

FREDERICK WINK, OF PHILADELPHIA, PENNSYLVANIA, ASSIGNOR TO
THOMAS DOLAN AND R. WILLIAMS, JR., OF SAME PLACE.

DESIGN FOR SHAWL-PATTERN.

Specification forming part of Design No. **6,856**, dated September 2, 1873; application filed August 9, 1873.
[Term of Patent 3½ years.]

H.

To all whom it may concern:

Be it known that I, FREDERICK WINK, of Philadelphia, Pennsylvania, have invented a Design for a Shawl-Pattern, of which the following is a specification:

The figure in the accompanying drawing fully represents my design for a shawl-pattern, which consists of a stripe or series of stripes, *a*, upon a plain ground, *B*. Each stripe *A* is composed of minor ornamental stripes *a*, *b*, *c*, and *d*, alternated with plain parallel stripes, bars, or ribs of different widths and shades or colors, some being strongly contrasted and others blended into each other, as shown. The stripes *a* and *c* are similar in design, each having a ribbed edging and an interior ornamented by dots and oblong figures, as repre-

sented. The stripes *b* and *d* are also similar, each being composed of a central bar, edged upon both sides with short transverse ribs and blocks, as shown.

Irrespective of the colors employed, I claim—

1. The design for the stripe *a*, as shown and described.
2. The design for the whole pattern, as described and represented.

In testimony whereof I have signed my name to this specification in the presence of two subscribing witnesses.

FRED. WINK.

Witnesses:

CLINTON M. LATOURETTE,
LEWIS T. GODFREY.
